EXPANSION RAIL JOINT

Clark D. Zumpe, McKeesport, Pa., assignor to National Tube Company, a corporation of New Jersey

Application December 19, 1938, Serial No. 246,703

4 Claims. (Cl. 238—222)

This invention relates to rail joints, and, particularly, to an improved rail joint of the expansion type, especially adapted for use in the runway track of traveling cranes and the like.

It is desirable, as is generally known, to provide at least some joints in the laying of rails which will permit the same to expand and contract due to changes in temperature so as to eliminate the "snaking" thereof. "Snaking" is the tendency of the rails to buckle or assume a curved shape, thereby resulting in varying the gage of the track and, at times, in the pulling of the rails from their ties or other fastenings. This, of course, is due to the compression action between the rail ends resulting from the expansion of the rails induced by a rise in temperature.

Various types of expansion rail joints have been suggested and used but, in most of these joints, a wide gap was left between the ends of the rails and one rail end would usually sag relative to the other when a wheel passed thereon, which usually resulted in the ends of the rail heads being upset after a time, due to the repeated impact of the wheels thereagainst. This repeated impact also placed an undue wear on the flanges of the wheels, thereby not only reducing the life of the rails and necessitating frequent replacements thereof but also materially reducing the life of the wheels.

Also, such rail joints were unsatisfactory in that a pounding usually occurred when the wheels passed over such a wide gap, thereby resulting in vibrations being transmitted throughout the crane or car.

According to the present invention, there is provided an improved rail joint of the expansion type in which all of the above disadvantages have been eliminated and, yet, one which will permit the rails to properly expand and contract at will.

It is one of the objects of the present invention to provide a simple and inexpensive improved expansion rail joint in which a continuity of the rail head is maintained at all times between the ends of the rails so as to provide a smooth joint which will satisfactorily permit expansion and contraction of the rails.

It is another object of the invention to provide an improved expansion rail joint in which the rail heads of the rails will, at all times, be positioned at one level relative to each other, and, at the same time, one in which the load thereon will be transmitted to the rails and not

to the connecting bolts, and one that can be easily assembled and maintained.

It is a further object of the invention to provide an improved expansion rail joint, in which the width of the rail head throughout the joint is at least 60 per cent of the width of the rail head of the rails.

Various other objects and advantages of this invention will be more apparent in the course of the following specification and will be particularly pointed out in the appended claims.

In the accompanying drawing there is shown, for the purpose of illustration, one embodiment which my invention may assume in practice.

In the drawing:

Figure 1 is a plan of the improved expansion rail joint of my invention;

Figure 2 is a side elevation thereof;

Figure 3 is a section taken on line III—III of Figure 2;

Figure 4 is a section taken on line IV—IV of Figure 2; and,

Figure 5 is a section taken on line V—V of Figure 2.

Referring more particularly to the drawing, there is shown a pair of rails 2 and 3 having rail heads 4 and 5, respectively, disposed upon the web portions 6 of the rails and oppositely disposed end portions 7 which are joined together by the improved expansion joint of my invention.

According to the present invention, the rail head 4 of the rail 2 is cut away from the end on one side of the web to a point intermediate the rail so as to provide a cavity or opening 8 in the rail head on that side of the rail and the rail head 5 of the rail 3 is similarly cut away from the end of the rail on the side of the web to a point intermediate the rail so as to provide a cavity or opening 9 in the rail head on the opposite side of the rail.

There is securely connected to the side of the rail 3, preferably by means of welding, a splice bar 10 having an upwardly extending portion 12 integral therewith which is adapted to extend upwardly with the top surface thereof flush with the top surface of the rail heads. This integral portion at least abuts against the end of the rail head 5 of the rail 3 and is preferably attached thereto or integral therewith, and is adapted to bridge the ends of the rails on that side and extend across and lie in the opening 8 next to the web in the side of the rail head 4 of the rail 2, and so arranged as to provide a clearance 13.

between the outer end of the integral portion 12 and the inner wall of the opening 8.

There is securely connected to the side of rail 2 on the opposite side of the rails, and similarly positioned, a like splice bar 14 having an upwardly extending portion 15 integral therewith which is adapted to at least abut against the end of the rail head 4 of the rail 2, and also preferably integral therewith, and to bridge the ends of the rails on that side and extend across and lie in the opening 9 next to the web on that side of the rail head 5 of the rail 3, and likewise arranged so as to provide a clearance 16 between the outer end of the integral portion 15 and the inner wall of the opening 9.

The upwardly extending integral portions 12 and 15 of the splice bars 10 and 14, respectively, are preferably formed by cutting away the metal from the respective rail heads from the end on the respective sides of the webs thereof, as shown at 17. The removed metal portions are then welded to the top edge of the respective splice bars and metal built on, as designated at 18, sufficiently to bridge across the ends of the rails and extend the proper distance into the respective openings 8 and 9. The splice bars are then welded to the sides of their respective rails with the removed metal portions being positioned in the openings in the rail heads caused by their removal and securely welded thereto so as to provide a continuation of the rail head on opposite sides of the respective rails. The built-on metal is preferably derived from a welding rod of the proper chemical composition to furnish strength and hardness equivalent to or preferably greater than the rail heads themselves. It will be understood that the rail ends to be joined are prepared in exactly the same manner. As a result, it will be seen, then, that the rails are interchangeable; that is, each of the rails is prepared as described on one side of the rail at one end thereof and on the opposite side at the other end.

In joining the rails after the splice bars have been attached respectively thereto, as described, it will be understood that the outer free end of the splice bar 10 is positioned next to the web of the rail 2 on the opposite side from that to which the splice bar 14 is attached thereto and the outer free end of the splice bar 14 is likewise positioned next to the web of the rail 3 on the opposite side from that to which the splice bar 10 is attached thereto. There is provided, in the outer free ends of each of the splice bars 10 and 14, elongated or slotted holes 19 which are adapted to align with circular holes 20 arranged through each of the webs of the rails and the ends of the splice bars connected thereto for receiving the track bolts 21.

The slotted holes 19 in the splice bars are elongated sufficiently to permit the requisite sliding motion between the webs of the rails, together with the splice bars attached thereto, and the outer free ends of the respective splice bars, due to the expansion and contraction of the rails.

It will be seen that, by providing an expansion joint of such construction, a continuous rail head is maintained throughout the joint and the width or bearing surface of the rail head throughout the same is at least 60 per cent of that of the rail heads of the rails; that is, the width or bearing surface of the rail head is not reduced more than 40 per cent at any section of the joint and this only for a distance equal to the amount the

joint is opened due to expansion and contraction of the rails.

As a result of my invention, it will also be seen that there is provided an expansion rail joint in which the load thereon will be carried substantially by the splice bars and the rails, thereby eliminating excessive forces being transmitted to the track bolts, the track bolts acting merely to hold the splice bars and the rail ends together and the rail ends in alignment with each other.

While I have shown and described one embodiment of my invention, it will be understood that this embodiment is merely for the purpose of illustration and description and that various other forms may be devised within the scope of my invention, as defined in the appended claims.

I claim:

1. An expansion joint for rails comprising rail ends having cavities arranged in the end portions of the rail heads of each of them, a splice bar disposed on each side of said rails for joining the rail ends together with one end of each of said splice bars being welded to each of the rails, and means integrally carried by each of said splice bars which is adapted to lie in the oppositely arranged cavity in the rail head of the opposed rail end so as to provide a continuation of the rail head between the ends of the rails, said means including metal built on the splice bars and securely welded thereto whose strength is greater than that of the rail heads, said splice bars and the integral means carried thereby being so constructed and arranged as to permit expansion and contraction of the rails.

2. An expansion joint for rails comprising rail ends having a cavity arranged in the end portion of the rail head of one of the rails next to the web on one side of the rails and a similar cavity arranged in the end portion of the rail head of the other rail next to the web on the opposite side of the rails, a splice bar disposed next to the web on each side of the rails and bridging the ends thereof with one of said splice bars being welded to the side of the rail on the side opposite that from the cavity therein, and the other splice bar being welded to the side of the other rail on the side opposite from the cavity therein, the opposite free ends of each of said splice bars extending freely along the respective sides of the rails on the side opposite to which the other is attached, upwardly extending means integrally carried by each of said splice bars which is adapted to lie in the oppositely arranged cavity in the rail head of the opposed rail end so as to provide a continuation of the rail head between the ends of the rails said means including metal built on the splice bars and securely welded thereto whose strength is greater than that of the rail heads, with the inner end of said integral means of each of said splice bars being securely welded to the rail head to which the respective splice bars are welded so as to provide a solid continuous rail head at the joint on that side of the rail, and means for movably attaching the free ends of said splice bars to the respective ends of the rails so as to permit expansion and contraction thereof.

3. An expansion joint for rails comprising rail ends having a portion of the rail head removed from the end portion of one of the rails on one side of the web on one side of the rails and a portion of the rail head removed from the end portion of the oppositely disposed rail on one side of the web on the other side of the rails so as to provide a cavity in each end portion thereof, a

splice bar disposed next to the web on each side of said rails and bridging the ends thereof with one of said splice bars being welded to the side of the rail on the side opposite that from the removed portion in that rail and the other splice bar being welded to the side of the other rail on the side opposite that from the removed portion in that rail, the opposite free ends of each of said splice bars extending freely along the respective 10 sides of the rails on the side opposite to which the other is attached and having slotted holes arranged therein for receiving a bolt, each of said splice bars having an upwardly extending portion integral therewith which is adapted to lie 15 in part of the cavity formed therein by the removed portion of said rails so as to provide a continuous rail head between the ends of the rails with the inner end of said integral portion of each of said splice bars being securely welded to the rail head to which the respective splice bars are welded so as to provide a solid continuous 20 rail head at the joint on that side of the rail and with the outer end of the integral portion on each of said splice bars being spaced from the inner wall of the respective cavities of the opposed rail ends in which they are disposed thereby providing a clearance therebetween so as to 25 permit expansion and contraction of the rails, said upwardly extending portion of each of said splice bars including metal built on the splice bars and securely welded thereto whose strength is greater than that of the rail heads.

4. An expansion joint for rails comprising rail ends having a portion of the rail head removed from the end of one of the rails on one side of the web on one side of the rails and a portion of the rail head removed from the end of the oppositely disposed rail on one side of the web on the other side of the rails so as to provide a cavity in each end portion thereof, a splice bar disposed next to the web on each side of said rails and bridging the ends thereof with one of said splice bars being welded to the side of the rail on the side opposite that from the removed portion in that rail and the other splice bar being welded to the side of the other rail on the side opposite that from the removed portion in that rail with the opposite free ends of each of said splice bars extending freely along the respective 10 sides of the rails on the side opposite to which the other is attached and having slotted holes arranged therein for receiving a bolt, each of said splice bars having an upwardly extending portion integral therewith which is adapted to lie in the 15 respective cavity so formed in the end of each of said rails so as to provide a continuous rail head between the ends of the rails with the inner end of said integral portion of each of said splice bars being securely welded to the rail head to 20 which the respective splice bars are welded so as to provide a solid continuous head at the joint on that side of the rail and with the outer end of the integral portion on each of said splice bars being spaced from the inner wall of the respective 25 cavity of the opposed rail end in which it is disposed thereby providing a clearance therebetween so as to permit expansion and contraction of the rails, said upwardly extending portion of each of said splice bars comprising the removed rail head 30 portions on that side of the rail web securely welded to the respective splice bars with additional metal built on and securely welded thereto whose strength is greater than that of the rail heads, said joint being constructed and arranged 35 so that the rail head throughout the joint is at least 60 percent of that of the rail head of each of the rails.

CLARK D. ZUMPE.
